UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

INSERT FEEDING AND CUTTING DEVICE.

1,392,470.

Specification of Letters Patent.

Patented Oct. 4, 1921.

Original application filed September 7, 1910, Serial No. 580,870. Patent No. 1,232,639, dated July 10, 1917. Divided and application filed June 29, 1917, Serial No. 177,652. Divided and this application filed January 31, 1919. Serial No. 274,218.

To all whom it may concern:

Be it known that I, HENRY A. WISE Wood, a citizen of the United States, residing at New York, in the county of New York and 5 State of New York, have invented a new and useful Insert Feeding and Cutting Device, of which the following is a specification.

This is a division of my application for 10 patent, Serial No. 177,652 filed June 29, 1917, which in turn is a division of my Patent No. 1,232,639 granted July 10, 1917, on a machine for making magazines and the like filed Sept. 7, 1910, Serial No. 580,870.

15 This invention relates to the art of printing books, magazines, and newspapers which are made up of several signatures, varying in character of paper and number of pages, together with inserts of one or more leaves.

20 The principal objects of this invention are to provide a magazine, book, or newspaper making machine with improved supplement, or insert, feeding mechanism and cutting mechanism, which constitute modifications of the forms shown and claimed in 25 the above mentioned patent. The invention also involves improvements in combinations of parts and details of construction as will appear.

30 Reference is to be had to the accompanying drawing, which is a diagrammatic side view of part of a magazine making machine constructed in accordance with this invention with arrangements for feeding an insert 35 to the front or back of the sheets from two of the decks of the press.

It is to be understood that the presses or 40 decks referred to in my above mentioned cases need not be of the same character, as it is one express purpose of those inventions to provide for using many types of printing presses in the same machine. In this character of work it is common to use both flat sheet bed and rotary web presses, and 45 it is preferred that the ordinary high-speed web presses be employed for the work that has been described above, and that flat presses be employed for the kind of work that has to be done more carefully and 50 accurately and at a slow speed, while a less high grade of work may be done by a press designed for that purpose. The present in-

vention is produced for the purpose of employing work from the low speed flat presses for the purpose of supplying inserts and 55 of doing so either with or without a sheet of tissue paper. It will be understood, of course, that these inserts may consist of a single sheet or a double sheet folded once to form a signature of two sheets, or twice 60 to form one of four sheets, etc.

In the form shown an insert feeding device is shown for feeding sheets which have been previously printed, so the press is not 65 illustrated. A flat bed or any other kind of press can be used of course, but it is preferred to use a press or presses capable of doing a high class of work. These flat sheets are fed by hand or mechanically from a feed board *g*. They may be of from two 70 to sixteen pages, or even more. They are fed between gages in the usual way to rolls 1 and are controlled by feed gages 2 so that the sheets are fed forward one at a time along a tape-run-way 3. If tissue sheets 75 are to be introduced, as is shown in this case, they are supplied with a line of paste by means of a paste blade 4 which moves to and from a paste roll 5. The tissue web 6 is fed at the proper speed to cutting cylinders 7 and cut up into sheets, and then fed to tapes 8 into contact with the insert sheets. They are then fed along the runway to either 80 of two cutting, collecting and folding cylinders *F*, being directed in the desired path 85 by a switch 9. It will be seen that the web *a* or *a*² also can be fed to the same cutting, collecting and folding device *F* as the insert, and that the insert is fed on the inside 90 of the web or on the outside so as to form what is technically known as an insert in one case and an onset in the other. In either case it is delivered to the gathering device *R* with the signature formed from the web of one of the decks of a coöperating press. 95 Means are shown for cutting the tissue web 6 into sheets of different lengths, and paste is applied to the tissue sheets instead of to the insert. One cutting cylinder 10 is shown to cut off two page lengths, and another 11 100 to cut off one page lengths. The proper one of these cylinders is thrown into contact with the large grooved cylinder as desired.

The combined cutting, collecting and fold-

ing devices can be constructed as is now common in this industry, the form shown comprising a folding cylinder f^5 and a cutting and collecting cylinder f^6 . The pins on the cylinder f^5 carry the sheet around the cylinder and impose it on the following sheet when the sheets are to be collected. In this form the pins are pivoted and mechanism which is well known in this art is provided to pull them into the cylinder to strip them from the sheet. This mechanism is not illustrated and described in full as it is so well known. The cylinder f^5 , which is shown as of twice the diameter of the cylinder f^6 , has pins f^{11} for carrying the sheets around to be folded. Folding blades f^{18} operate in the usual manner to fold the sheets into the rolls f^{14} , cam rolls f^{15} being employed as usual. The folded signature is guided by the guides f^{16} to the gathering drum where it is received by pins r' , grippers or the like. In this case these pins are shown as mounted on levers r^2 actuated by springs r^5 to transfer the signatures to the gathering drum R. These levers have cam rollers r^3 which are operated by a cam (not shown) to withdraw the pins periodically. It will be understood, of course, that other equivalents of this mechanism can be employed so long as a plurality of elements are located along the operating surface of the gathering device to take the signatures from the several printing machines or decks and deliver them to the gathering device which takes them up and delivers them in the proper order to the delivery cylinder which will be described hereinafter.

Whatever form of press is used for producing the main product and the ordinary signatures of the magazine, and whatever inserts and smaller signatures, it will be obvious that these various products will be delivered one by one to the gathering drum in a predetermined order, and that during a complete revolution thereof the entire magazine will be applied to it, except the cover.

While I have illustrated and described only one form of the invention and of different parts thereof, I am aware that many modifications can be made and that as far as most of the features of the invention are concerned, they do not depend upon the details of construction. Therefore I do not wish to be limited to the details of construction shown, except as expressed in the claims, but what I do claim is:—

1. In a printing press, the combination with means for receiving insert sheets of means for feeding a web, a cylinder for receiving the web, a plurality of cutting cylinders each adapted to be brought into operative engagement with said cylinder for dividing the web into sheets, said cutting cylinders having different numbers of cut-

ting knives thereon, and means for associating the sheets cut thereby with the insert sheets.

2. In a machine of the character described, the combination with means for receiving insert sheets of a grooved cylinder for receiving a web, a cutting cylinder having a single knife thereon movable to and from operative position with respect to the grooved cylinder, a second cutting cylinder having a plurality of knives thereon movable to and from operative position with respect to the grooved cylinder, and means for associating the sheets cut thereby with the insert sheets. 80

3. In an insert feeding device the combination with means for receiving insert sheets of means for cutting up the web into sheets, comprising a cylinder for receiving a web, two movable cutting cylinders, one having one knife and the other having two knives, each cutting cylinder being adapted to be brought into coöperative relation to the first named cylinder when the other is out of operation, and means for associating the sheets cut thereby with the insert sheets. 85

4. In an insert and tissue feeding device, the combination of a runway for receiving one set of sheets, means for feeding the other web, means for cutting the web into sheets, means for pasting one set of sheets, means for feeding the other sheets into contact with the pasted sheets, two cutting and collecting devices, means for feeding the insert and tissue sheets to either of said devices, and a gathering device for receiving signatures from both of said devices. 95

5. In an insert feeding device, the combination of a runway for receiving the insert sheets, means for feeding a tissue web, two cutting cylinders either one being adapted to be placed in operative position, each one being adapted to cut the tissue into different lengths, means for pasting the tissue sheets, means for feeding the pasted tissue sheets into contact with the insert sheets, two cutting and collecting devices, means for feeding the insert and tissue sheets to either of said devices, and a gathering device for receiving signatures from both of said devices. 110

6. In an insert feeding device, the combination of a runway for receiving the insert sheets, means for feeding a tissue web, means for cutting the tissue into sheets, means for pasting the tissue sheets, means for feeding the cut tissue sheets into contact with the insert sheets, two cutting and collecting devices, means for feeding the insert and tissue sheets to either of said devices, means for feeding a printed web to one of said devices to receive the insert on one side of it, and a gathering device for receiving signatures from both of said devices. 120

7. In an insert feeding device, the combination of a runway for receiving the insert sheets, means for feeding a tissue web, two cutting cylinders either one being adapted to be placed in operative position, each one being adapted to cut the tissue into different lengths, means for pasting the tissue sheets, means for feeding the pasted tissue sheets into contact with the other web, means for cutting the web into sheets, means for pasting one set of sheets, means for feeding the other sheets into contact with the pasted sheets, collecting devices, means for feeding the insert and tissue sheets to said devices, and a gathering device for receiving signatures from said devices. 30
- 10 insert sheets, collecting devices, means for feeding the insert and tissue sheets to said devices, and a gathering device for receiving signatures from said devices. 35
8. In an insert and tissue feeding device, the combination of a runway for receiving one set of sheets, means for feeding the other web, means for cutting the web into sheets, means for pasting one set of sheets, means for feeding the other sheets into contact with the pasted sheets, collecting devices, means for feeding the insert and tissue sheets to said devices, and a gathering device for receiving signatures from said devices. 40
- 15 20 25 30 35 40 45 50
9. In an insert and tissue feeding device, the combination of a runway for receiving one set of sheets, means for feeding the

other web, means for cutting the web into sheets, means for pasting one set of sheets, means for feeding the other sheets into contact with the pasted sheets, collecting devices, means for feeding the insert and tissue sheets to said devices, means for feeding a web from a high speed press to said devices, and a gathering device for receiving signatures from said devices.

10. In an insert feeding device, the combination of a runway for receiving the insert sheets, means for feeding a tissue web, two cutting cylinders either one being adapted to be placed in operative position, each one being adapted to cut the tissue into different lengths, means for pasting the tissue sheets, means for feeding the pasted tissue sheets into contact with the insert sheets, collecting devices, means for feeding the insert and tissue sheets to said devices, means for feeding a web from a high speed press to said devices, and a gathering device for receiving signatures from said devices.

In testimony whereof I have hereunto affixed my signature.

HENRY A. WISE WOOD.
